FIG. 1 is a perspective view of an operating handle for a fork lift truck or the like taken from the rear and one side showing my new design, it being understood that the opposite side is a mirror image thereof;

FIG. 2 is a rear elevational view thereof;

FIG. 3 is a front perspective view thereof;

FIG. 4 is an enlarged fragmentary perspective view of the lower portion thereof taken from the front and one side; and

FIG. 5 is a rear elevational view of FIG. 4.

The broken lines in the drawing are for illustrative purposes only.

This is a division of design application Ser. No. 332,177, filed Feb. 13, 1973, and now abandoned.

I claim:

The ornamental design for an operating handle for a fork lift truck or the like, as shown and described.
